UNITED STATES PATENT OFFICE.

ALBERT S. HOWELL, OF CHICAGO, ILLINOIS, ASSIGNOR TO THE BELL & HOWELL COMPANY, OF CHICAGO, ILLINOIS, A CORPORATION OF ILLINOIS.

MOTION-PICTURE PROJECTING MACHINE.

Application filed August 16, 1924. Serial No. 732,469.

One of the features of the invention relate to the provision of means for effecting unattended operation of a motion picture projecting machine for long periods of time 5 without the use of an endless film and its attendant disadvantages. The invention contemplates reversing the direction of feed of the film at opposite ends of a predetermined travel of the same, as fed by the feeding mechanism of the projecting machine, whereby the film is reeled off of and onto the usual film reels employed on projecting machines.

Other features of the invention relate to 15 means for interrupting the projecting light on the film during stoppage or reversal of the film whereby to prevent damage to the film by reason of the projecting light playing too long on one portion of the film, 20 thus permitting a very intense projecting light being used without danger of injury to the film.

With these features in view my invention consists in certain features of novelty 25 in the construction, combination, and arrangement of parts by which the said features and certain other features, hereinafter appearing, are effected, all as fully described with reference to the accompanying drawings 30 and more particularly pointed out in the claims.

In the said drawings—

Figure 1 is a top plan view of a motion picture projecting machine with parts broken 35 away.

Figures 2 and 3 are enlarged sectional views on the line 2—2 of Fig. 1 with a part broken away.

Figure 4 is a partial section on the line 40 4—4 of Fig. 3.

Figure 5 is a partial section on the line 5—5 of Fig. 2.

Figure 6 is an interior view on the line 6—6 of Fig. 1 with parts removed.

Figure 7 is an interior view on the line 45 7—7 of Fig. 1 partially in section and partially broken away.

Figure 8 is a partial section on the line 8—8 of Fig. 9.

Figure 9 is an enlarged partial section on the line 9—9 of Fig. 7.

Figure 10 is a partial side elevation of

the projecting machine with parts broken away and in section.

Figure 11 is an enlarged partial section 55 on the line 11—11 of Fig. 7.

Like characters of reference indicate like parts in the several views.

Referring to the drawings the feeding mechanism of the projecting machine embodies an intermittent film feeding mechanism for intermittently moving the film through an apertured film guide 1 and constant feed sprockets 2 operating in correspondence with the intermittent feeding 60 mechanism for feeding the film between the guide 1 and respective of film reels mounted on spindles 3 of the machine, all as is usual. See Fig. 1. Projecting light from a lamp within a lamp chamber 4 to the 70 rear of the feed guide projects light upon the film at the aperture of the guide 1 and the image on the film is projected thereby through a lens 5 in front of the aperture of the guide, a shutter, operated with the feeding mechanism, periodically interrupting the projecting light during intermittent movement of the film in the guide, all as is usual.

An electric motor 6 is assembled in the 80 frame of the projecting machine, and is disposed to one side of the lamp chamber 4 on a horizontal forwardly and rearwardly extending axis. The shaft 7 of the motor extends forwardly from the motor, and secured on this shaft adjacent its front end is an air impeller wheel 8 which is disposed in an air chamber 9 formed in the frame of the machine and extending transversely between the guide 1 and the lamp 85 chamber 4. This air chamber communicates with the aperture of the guide through a registering aperture 11 in the frame of the machine, see Fig. 9, and through which the projecting light passes, and also communicates with the lamp chamber 4 through suitable passages, not shown, whereby to maintain a current of air on the film at the aperture of the guide and through the lamp chamber when the impeller wheel is driven by the motor for the dissipation of heat. When in operation the impeller wheel draws air through openings 12 in the portion of the frame of the machine forming the motor 90 95 100.

housing and then through a large aperture 13 in the wall of the frame between the air chamber and the motor housing portion of the frame.

5 The motor 6 drives the film feeding mechanism and shutter through the medium of a releasable friction clutch in the following manner. See Fig. 10. A spur driving pinion 14 is rotatably mounted on the motor 10 shaft 7 in front of the hub of the impeller wheel 8 and meshes with suitable gearing for driving the feeding mechanism and shutter. Friction washers 15 are respectively disposed in front of the pinion and 15 between the rear end of the pinion and the hub of the impeller wheel 8. A cylindrical member 16 is secured on the front end of the motor shaft, and a plurality of pivotally mounted wedge members 17 are engaged in 20 respective radial slots in the motor shaft between the cylindrical member 16 and the forward washer 15. A circular coiled tension spring 18 encircles the shaft 7 and engages outwardly facing concave surfaces of 25 the wedge members 17 for yieldably urging the wedge members inwardly to engage the forward washer 15 and to press the washers 15 and the pinion 14 therebetween against the hub of the impeller wheel 8 whereby to 30 frictionally drive the pinion from the motor shaft for driving the feeding mechanism and shutter from the motor. A stud member 19 is mounted for longitudinal movement in a concentric bore 21 in the forward 35 end of the motor shaft, and is provided with an intermediate reduced portion 22. Portions of the wedge members 17 project into the bore 21 for cooperation with the stud 19 to release and engage the clutch with longitudinal movement of the stud. Thus, when 40 the stud is positioned, as shown in Fig. 10, so that the reduced portion 22 of the stud permits inward movement of the wedge members under the influence of the spring 45 18, the clutch is engaged as before described. When the stud is moved to a rearward position the large portion of the stud moves the wedge members 17 outwardly against the influence of the spring 18 and releases the 50 clutch by suspending the compression of the washers 15 and pinion 14 against the hub of the impeller wheel 8, a shallow circumferential groove 23 on the stud immediately in front of the reduced portion 22 thereof being engaged by the wedge members 17 under 55 the influence of the spring 18 to releasably maintain the clutch disengaged.

60 A clutch lever 24 is pivoted at 25 on a horizontal axis and has an arm provided with a roller 26 which is engaged in a circumferential groove 27 on the forward end of the stud 19 for shifting the stud longitudinally to engage and disengage the clutch as heretofore described. The main 65 portion of the lever 24 is disposed exte-

riorly of the frame of the machine for manual operation and sweeps in front of a wall thereof, stops 28 on the frame limiting movement of the lever in both directions.

70 The reel spindles 3 are alternately driven with the film feeding mechanism to take up the fed film depending upon the direction of operation of the film feeding mechanism as is usual by a belt and pulley mechanism 29. See Fig. 1.

75 A motion picture projecting machine of the character described herein is described and claimed in my co-pending application, Serial No. 572,170, filed July 1, 1922, for motion picture projecting machine and the 80 like, and needs no further description for the present purposes.

85 The motor 6 is of a usual type, and the rear end of the housing thereof is formed by a removable end cap 31 which carries the motor brushes 32, see Fig. 6, which engage the commutator 33 at the rear end of the armature of the motor. Mounted on the inside of the end cap 31 for pivotal movement 90 on the axis of the motor shaft is a switch member 34 of insulating material, and mounted on this member are a pair of metal contacts 35 which alternately contact opposite brushes 32 in opposite positions of the member 34. The contacts are provided with 95 spring clips 36 in which the motor circuit wires are secured. Thus is formed a reversing switch and the arrangement is such that when the member 34 is at one end of its movement the motor operates in one direction and when the member 34 is at the other end of its movement the motor operates in the opposite direction. A stud 37 secured on the member 34 extends rearwardly therefrom through an opening in the cap 31 so 100 that the member 34 may be operated from the outside of the motor housing, the opening serving to limit movement of the member 34 at both ends of its movement. A plurality of radially disposed compression 105 spring devices 38 are disposed between the end cap 31 and the switch member 34 and serve to yieldably maintain the member 34 at either end of its movement by reason of 110 their axes passing on both sides of the pivotal axis of the member 34 in its movement 115 in an obvious manner.

120 Referring to Figs. 1, and 2-5 inclusive, a second cap member 39 is secured on the rear end of the end cap 31 and forms an enclosure therewith. Pivottally mounted on an axis coincident with the pivotal axis of the switch member 34, by means of a stud 41 secured on the transverse wall of the cap member 39, is a bell crank lever 42, one of the arms of which is provided with a slot embracing the stud 37 so that the reversing switch may be operated by the lever in both directions. The main portion of this bell 125 crank lever together with the other arm 130

thereof is bifurcated in a plane normal to the pivotal axis of the lever, and disposed in the space provided by the bifurcated portion of the lever and journaled on the stud 6 41 is a stop gear 43. A second stop gear 44 is disposed in the space provided by the bifurcated portion of the lever and is journaled on a stud 45 which is removably secured on the other arm of the lever by means 10 of a headed screw 46. The stop gears 43 and 44 mesh and cooperate with each other as hereinafter described and are preferably constructed for cooperation as follows. The teeth of these gears are formed similar to 15 ordinary spur gear teeth except as follows. The teeth of the gear 43 are normal except that one flute 47 thereof is relatively shallow, and one tooth 48 of the gear 44 is a normal tooth whereas the remainder of the teeth of 20 this gear are relatively short, they being cut off substantially at the pitch line of the gear. The gears 43 and 44 have different numbers of teeth, as shown the gear 43 having 52 teeth and the gear 44 having 53 teeth, and cooperate in the following manner. In the rotation of the gears 43 and 44 the short teeth of the gear 44 clear the 25 shallow flute 47 and the long tooth 48 of the gear 44 engages in the normal flutes of 30 the gear 43 until by reason of the progressive tooth engagement caused by the difference in the number of teeth in the gears the long tooth 48 engages in the shallow flute 47 and 35 interrupts rotation of the gears in the direction of rotation, as shown in Figs. 2 and 3. This action takes place in the rotation of the gears in both directions as is obvious, and is utilized as hereinafter described.

Rotatably mounted on a stud 49 secured on 40 the transverse wall of the cap member 39 is a spur pinion 51 and carried on a hub of the pinion is a large bored spur gear 52 which is connected with the pinion to drive the same by a yieldable friction clutch consisting of a pair of friction washers 53 disposed on opposite sides of the gear and 45 engaging the web thereof, a compression spring 54, and a nut 55 screwthreaded on the outer end of the hub of the pinion 51 and compressing the spring 54, washers 53 and the web of the gear 52 against the main portion 50 of the pinion. See Figs. 2, 3, and 4. A spur driving pinion 56 is secured on the rear end of the shaft 7 of the motor and meshes 55 with the gear 52 for driving the same from the motor.

Another stud 57 is secured on the transverse wall of the cap member 39, and a gear unit consisting of a pinion 58 and a large 60 spur gear 59 secured therewith is rotatably mounted thereon. The gear 59 meshes with the pinion 51, and the pinion 58 meshes with the stop gear 43, thus completing a reduction gear train for driving the stop gear 43 from the motor. The teeth of the pinion

58 are relatively short, they being cut off substantially at the pitch line thereof, to clear the shallow flute 47 of the gear 43.

In the operation of the motor the stop gear 43 is driven through the reduction gearing, 70 and the stop gear 44 rotates with the gear 43 until the long tooth 48 engages the shallow flute 47. When this engagement is made rotation of the stop gears 43 and 44 is suspended, whereupon the lever 42 is moved 75 with the gear 43 to operate the reversing switch to reverse the motor. Fig. 2 shows the position of the parts just as the long tooth 48 and the shallow flute 47 engage, and Fig. 3 shows the position of the parts 80 after the bell crank lever has been moved to the opposite end of its movement. Upon reversal of the motor the stop gears 43 and 44 rotate on each other in the opposite direction until the long tooth 48 again engages the shallow flute 47 whereupon the lever 42 is again actuated to operate the reversing switch to reverse the motor.

The yieldable friction clutch between the pinion 51 and gear 52 compensates for the 90 momentum of the motor and film feeding mechanism during reversal to prevent undue strain on the parts of the mechanism.

Thus the motor is automatically reversed at substantially equal intervals in the operation thereof, and when the clutch for driving the film feeding mechanism from the motor is engaged the film feeding mechanism is automatically reversed at opposite ends of a predetermined travel of a film fed by 95 the feeding mechanism. 100

Thus it will be observed that the machine is capable of unattended and automatic operation for long periods of time, and that to effect such operation an endless film is 105 not employed with attendant disadvantages.

The period of operation of the motor between reversals may be shortened by substituting for the stop gear 44 another stop gear having the same pitch and number of teeth with more than one long tooth for cooperation 110 with the shallow flute 47 of the stop gear 43, and it is for this reason that the stud 45 upon which the gear 44 is mounted is removably mounted on the bell crank 115 lever 42 as hereinabove described.

The stud 37 extends outwardly through a suitable opening in the cap 39 for manual operation of the reversing switch. See Fig. 1.

In order that a projecting light of relatively great intensity may be used without danger of injury to the film during reversal of the motor and film feeding mechanism means is provided whereby the projecting light on the film is automatically interrupted during stoppage or reversal of the motor and permitted to function during normal operation of the motor.

Accordingly the air chamber 9 is provided 120

with a vertically disposed cylinder formation 61 of rectangular cross section disposed above the aperture 11 and having its lower end open and communicating with the air chamber. See Figs. 7, 8, and 9. Secured in the air chamber at one side of the aperture 11 is a vertically disposed slotted guide 62. A shutter 63 disposed in a vertical transverse plane is provided with a lateral extension 64 at its lower end formed to interlock with the slotted guide 62 for guiding the lower end of the shutter for vertical movement. Secured to the upper end of the shutter is a horizontally disposed rectangular piston 65 which is engaged in the cylinder formation 61 for vertical movement therein and cooperates with the slotted guide 62 and extension 64 for guiding the shutter for vertical movement. The shutter 63 and the piston 65 attached thereto are, under the influence of gravity, urged to the lower end of their movement and when in this position the shutter is closed and lies in back of the aperture 11 and prevents the projecting light from passing therethrough onto the film in the aperture of the guide 1, as shown in Figs. 7 and 9. When the shutter and piston are at the upper end of their movement, as shown in dotted lines in Fig. 7, the shutter is open and is disposed above the aperture 11 to permit the projecting light to pass through the aperture 11 onto the film. The upper end of the cylinder formation above the piston is closed and communicates with the atmosphere by means of an air passage 66 and an exposed port 67 on the wall of the frame over which the aforementioned clutch lever 24 sweeps for purposes hereinafter described.

40 Rotation of the impeller wheel 8 by the motor in either direction creates air pressure in the air chamber and acts on the lower side of the piston 65 to move the same, together with the shutter, upwardly where-
45 by to open the shutter, the passage 66 and port 67 preventing a counter pressure being developed above the piston. When the motor is stopped or reversed the pressure in the air chamber 9 drops and the piston and shutter move downwardly under the influence of gravity into closed position until the air pressure in the air chamber is sufficient to again lift the piston and shutter. Thus the shutter is automatically operated to in-
50 terrupt the projecting light during stoppage or reversal of the motor and to permit the projecting light to function during normal operation of the motor, and when the film feeding mechanism is being driven by the
55 motor through the engagement of the hereinbefore mentioned clutch for driving the feeding mechanism from the motor the shutter is automatically operated to interrupt the projecting light on the film during stop-
60 page or reversal of the feeding mechanism

and to permit the projecting light to function during normal operation of the feeding mechanism.

The hereinbefore mentioned clutch lever 24 in its movement to engage and disengage the clutch for driving the film feeding mechanism from the motor sweeps over the port 67 and forms a valve therewith. The port 67 is so arranged that when the clutch lever is in clutch engaging position, as shown in Figs. 1 and 10, the port 67 is open and functions as hereinbefore described. When, however, the clutch lever is in clutch disengaged position, as partially shown by dot and dash lines in Fig. 10, it overlies the port 67 and closes the same. This closing of the port 67 permits equal pressure being developed above and below the piston 65, the air passing upwardly between the piston and cylinder formation, whereupon the shutter 63 and piston 65 move downwardly into closed position while the motor and air impeller are operating and the film feeding mechanism is stopped by reason of the driving clutch being disengaged.

In order that the shutter may be opened when the motor is operating and the feeding mechanism is stopped by reason of the disengagement of the driving clutch, a valve 68 is provided which communicates with the cylinder formation 61 above the piston 65, and is spring pressed into closed position and may be manually opened to lower the pressure above the piston to open the shutter.

While I have herein shown and particularly described the preferred embodiment of my invention I do not wish to be limited to the precise details of construction shown as changes may readily be made without departing from the spirit of my invention, but—

Having thus described my invention I claim as new and desire to secure by Letters Patent the following:

1. In a motion picture projecting machine the combination with a driven film feeding mechanism, of means for reversing the direction of operation of the feeding mechanism, a pivoted member for operating said reversing means, a revoluble stop gear disposed coaxial with the pivoted member, a second revoluble stop gear carried by the pivoted member and meshing with the first mentioned stop gear and cooperating therewith, and means for driving said first mentioned stop gear with the film feeding mechanism whereby to operate said pivoted member to operate said reversing means to effect reversal of the direction of operation of the feeding mechanism at opposite ends of a predetermined travel of a film fed by said feeding mechanism.

2. In a motion picture projecting machine the combination with a driven film feeding mechanism, of means for reversing the di-

rection of operation of the feeding mechanism, a pivoted member for operating said reversing means, a revoluble stop gear disposed coaxial with the pivoted member, a second revoluble stop gear carried by the pivoted member and meshing with the first mentioned stop gear, said stop gears having different numbers of teeth and one having a flute thereof relatively shallow and the other having teeth thereof relatively short to clear said shallow flute in the rotation of the gears and having a long tooth cooperating with said shallow flute to interrupt rotation of the gears whereby to effect movement of the pivoted member to operate said reversing means, and means for driving said first mentioned stop gear with the film feeding mechanism.

3. In a motion picture projecting machine the combination with a driven film feeding mechanism, of means for reversing the direction of operation of the feeding mechanism, a pivoted member for operating said reversing means, a revoluble stop gear disposed coaxial with the pivoted member, a second revoluble stop gear carried by the pivoted member and meshing with the first mentioned stop gear, said stop gears having different numbers of teeth and one having a flute thereof relatively shallow and the other having teeth thereof relatively short to clear said shallow flute in the rotation of the gears and having a long tooth cooperating with said shallow flute to interrupt rotation of the gears whereby to effect movement of the pivoted member to operate said reversing means, and means for driving said first mentioned stop gear with the film feeding mechanism including reduction gearing and a yieldable friction clutch adapted to compensate for momentum during reversal of the film feeding mechanism and said reduction gearing including a pinion meshing with said first mentioned stop gear and having relatively short teeth to clear said shallow flute.

4. In a motion picture projecting machine the combination with an electric motor for operating the same in either direction, of switch means for reversing the motor, a pivoted member for operating the switch means, a revoluble stop gear disposed coaxial with the pivoted member, a second revoluble stop gear carried by the pivoted member and meshing with the first mentioned stop gear, said stop gears having different numbers of teeth and one having a flute thereof relatively shallow and the other having teeth thereof relatively short to clear said shallow flute in the rotation of the gears and having a long tooth cooperating with said shallow flute to interrupt rotation of the gears whereby to effect movement of the pivoted member to operate said switch means to reverse the motor, and means for driving

said first mentioned stop gear from the motor including reduction gearing and a yieldable friction clutch adapted to compensate for momentum during reversal of the motor and said reduction gearing including a pinion meshing with said first mentioned stop gear and having relatively short teeth to clear said shallow flute.

5. In a motion picture projecting machine the combination with a driven film feeding mechanism, of a shutter movable into and out of position to interrupt the projecting light on a film fed by said feeding mechanism, an air impelling device driven with the feeding mechanism, means for automatically reversing the direction of operation of said feeding mechanism and said impelling device at opposite ends of a predetermined travel of a film fed by said feeding mechanism, and pneumatic means responsive to air affected by the operation of said impelling means for causing the shutter to be closed during reversal of the feeding means and to be open during operation of the feeding means between reversals thereof.

6. In a motion picture projecting machine the combination with a driven film feeding mechanism, of a shutter movable into and out of position to interrupt the projecting light on a film fed by said feeding mechanism and yieldably urged into closed position, an air blower driven with the feeding mechanism, means for automatically reversing the direction of operation of said feeding mechanism and air blower at opposite ends of a predetermined travel of a film fed by said feeding mechanism, and pneumatic means responsive to air affected by the operation of said blower for operating said shutter into open position and maintaining it in open position during operation of the feeding mechanism and blower between reversals and permitting the shutter to close during reversals of the feeding mechanism and blower.

7. In a motion picture projecting machine the combination with a film feeding mechanism and an electric motor for driving the same in both directions, of a switch for reversing the motor, means driven by the motor for automatically operating said switch to reverse the motor at predetermined substantially equal intervals in the operation thereof, a shutter movable into and out of position to interrupt the projecting light on a film fed by said feeding means, an air impeller driven by the motor in both directions, and pneumatic means responsive to air affected by said impeller for effecting closure of the shutter during reversal of the motor and opening of the shutter during normal operation of the motor.

8. In a motion picture projecting machine the combination with a film feeding means and an electric motor for driving the same

- in both directions, of a switch for reversing the motor, means driven by the motor for automatically operating said switch to reverse the motor at predetermined substantially equal intervals in the operation thereof, a shutter movable into and out of position to interrupt the projecting light on a film fed by said feeding means and yieldably urged into closed position, an air blower driven by the motor in both directions, and pneumatic means responsive to air affected by operation of said air blower for moving said shutter into and maintaining it in open position during normal operation of the motor. 10
9. In a motion picture projecting machine the combination with a film feeding mechanism, an electric motor and a releasable clutch for driving the feeding mechanism from the motor in both directions, of switch means for reversing the motor, means operated by the motor for automatically operating said switch means to reverse the motor at predetermined substantially equal intervals in the operation of the motor, means for interrupting the projecting light on a film fed by said feeding means and adapted to be rendered non-effective, means for automatically causing said interrupting means to interrupt the projecting light during stoppage or reversal of the motor and to be non-effective during normal operation of the motor, and means for causing said interrupting means to interrupt the projecting light while said clutch is released and permitting control of the interrupting means by said means for automatically controlling the interrupting means when the clutch is engaged. 30
10. In a motion picture projecting machine the combination with a film feeding mechanism, an electric motor and a manually controlled releasable clutch for driving the feeding mechanism from the motor, of a switch for reversing the motor, means operated by the motor for automatically operating said switch to reverse the motor at predetermined substantially equal intervals in the operation of the motor, a shutter movable into and out of position to interrupt the projecting light on a film fed by said feeding mechanism, an air impeller driven by the motor independently of said clutch, pneumatic means responsive to air affected by the operation of said impeller for causing said shutter to be closed during stoppage and reversal of the impeller and motor and to be open during normal operation of the impeller and motor, and means for causing said shutter to be closed during release of said clutch and permitting control of the shutter by said impeller when the clutch is engaged. 50
11. In a motion picture projecting machine the combination with a film feeding mechanism, an electric motor and a manually controlled releasable clutch for driving the feeding mechanism from the motor, of a switch for reversing the motor, means operated by the motor for automatically operating said switch to reverse the motor at predetermined substantially equal intervals in the operation of the motor, a shutter movable into and out of position to interrupt the projecting light on a film fed by said feeding mechanism and yieldably urged into closed position, an air blower permanently connected to the motor to be driven thereby, pneumatic means responsive to air impelled by said air blower for causing said shutter to open and remain open during normal operation of the blower and motor and permitting the shutter to close during stoppage or reversal of the motor and blower, and an air valve controlled with said clutch for rendering said pneumatic means unresponsive to air affected by the operation of the blower during release of the clutch and permitting response while the clutch is engaged. 70
12. In a motion picture projecting machine the combination with a film feeding mechanism and a releasable clutch for driving the feeding mechanism, of means for interrupting the projecting light upon a film fed by said feeding mechanism and adapted to be rendered non-effective, and means whereby said interrupting means is controlled with the clutch to interrupt the projecting light when the clutch is released and to permit cooperation of the projecting light with the film when the clutch is engaged. 90
13. In a motion picture projecting machine the combination with a film feeding mechanism, a driving means and a releasable clutch for driving the feeding mechanism from the driving means, of a shutter movable into and out of position for interrupting the projecting light on a film fed by said feeding mechanism, air impelling means driven by said driving means independently of said clutch, pneumatic means responsive to air affected by operation of said impelling means for effecting opening of the shutter during operation of said air impelling means and closing thereof during non-operation of said air impelling means, and means whereby the shutter is caused to close with release of the clutch and permitted to open when the clutch is engaged. 100
14. In a motion picture projecting machine the combination with a film feeding mechanism, an electric motor and a releasable clutch for driving the feeding mechanism from the motor, of a shutter movable into and out of position for interrupting the projecting light on a film fed by said feeding mechanism and yieldably urged into closed position, air impelling means permanently connected with the motor to be 120
- 125
- 130

driven thereby, pneumatic means responsive to air affected by operation of said impelling means for operating the shutter into and maintaining the same in open position, and
5 means whereby the shutter is caused to close with release of the clutch and permitted to open when the clutch is engaged including

an air valve for rendering said pneumatic means unresponsive to air affected by operation of said impelling means. 10

In witness whereof I hereunto affix my signature this 13th day of August, 1924.

ALBERT S. HOWELL.
